ENVELOPE MACHINE

Abraham Novick, Flushing, N. Y., assignor to
 F. L. Smithe Machine Co., Inc., New York, N. Y.,
 a corporation of New York

Application October 2, 1931, Serial No. 566,462
 Renewed February 5, 1937

16 Claims. (Cl. 93—62)

This invention relates to envelope machines, and has for an object the provision of a machine which is built substantially in a single vertical longitudinal plane, and is of moderate length so that each machine will occupy little space in a factory and a plurality of the machines may be arranged in parallel relation without waste space between them.

To this end it is a feature of the invention that 10 the machine comprises a linear outgoing stretch of mechanism adapted to gum, fold, and adhesively unite the side flaps of open end envelope blanks, and a return stretch adapted to gum the bottom flap and to fold the bottom and top flaps, 15 the two stretches being disposed one above the other and being located in the same longitudinal vertical plane.

It is a further important object of the invention usable in conjunction with, or independently 20 of, the above-mentioned object to provide a machine including a mechanism for gumming and folding the side and bottom flaps of the envelope blanks and for folding the top flap in conjunction with a plurality of means selectively usable 25 for supplying blanks to said mechanism, the first including a gummer and drier for the top flaps which may be rendered idle at will independently of the other parts of the machine, and the other comprising means for delivering fresh blanks in 30 stack form to the gumming and folding mechanism. Such a machine is adapted either to make envelopes having the top flaps thereof gummed for sealing or having said flaps un-gummed for use in carrying second class mail. 35 In the latter case the entire gumming and drying mechanism for the top flaps is rendered idle, so that the power normally consumed in driving such mechanism and the wear upon the parts thereof are saved when the mechanism is not 40 being usefully employed.

Other objects and advantages will hereinafter appear.

In the drawings forming part of this specification:

45 Figure 1 is a diagrammatic, side elevation of the end of the machine used as the introductory end when the top flap gumming and drying mechanism is employed;

Figure 2 is a diagrammatic, plan view showing 50 blank turning mechanism employed in Figure 1;

Figure 3 is a diagrammatic, side elevation of a portion of the machine which adjoins that of Figure 1;

Figure 4 is a diagrammatic, plan view of a 55 portion of the mechanism illustrated in Figure 3;

Figure 5 is a diagrammatic, side elevation of a portion of the machine which adjoins that of Figure 3;

Figure 6 is a diagrammatic, plan view illustrating portions of the mechanism shown in 5 Figure 5;

Figure 7 is a diagrammatic, side elevation of a portion of the machine which adjoins that of Figure 5;

Figure 8 is a diagrammatic, plan view, illustrating a portion of the mechanism shown in 10 Figure 7;

Figure 9 is a diagrammatic, side elevation of a portion of the machine which adjoins that of Figure 1, and which is located above it; 15

Figure 10 is a top view of a portion of the mechanism illustrated in Figures 1 and 9 which aligns the blanks and carries them to the upper level;

Figure 11 is a diagrammatic, plan view of another portion of the mechanism illustrated in 20 Figure 9;

Figure 12 is a diagrammatic, side elevation of a portion of the machine which adjoins that of Figure 9 and which is located above that of 25 Figure 3;

Figure 13 is a diagrammatic, plan view showing parts of the mechanism illustrated in Figure 12;

Figure 14 is a diagrammatic, sectional view on 30 a larger scale than that of Figure 1, illustrating mechanism for fanning out the stacked blanks and gumming the sealing flaps thereof;

Figure 15 is a fragmentary, side elevation similar to that of Figure 14, and illustrating the delivery of the gummed blanks to the drier; 35

Figure 16 is a detail view in sectional elevation, partly broken away, illustrating the feeding of the blanks delivered by the drier mechanism to the side flap gumming and folding mechanism; 40 and

Figure 17 is a view similar to Figure 16, illustrating the delivery of fresh blanks from a stack to the side flap gumming and folding mechanism, the drier mechanism and associated parts being idle. 45

If Figures 1, 3, 5 and 7 are laid end to end in the order named at the line A, A, B, B and C, C, Figures 1 and 9 are laid side to side at the lines D, D, and Figures 9 and 12 are laid end to end at 50 the lines E, E, the machine is seen in its entirety in side elevation, with the exception that the conveyor shown at the left hand end of Figure 12 for accumulating the finished envelopes is broken away.

For making envelopes whose top flaps have gum applied to them the fresh blanks are introduced in stack form from a table 4 at the right hand end of Figure 1. The blanks are taken one by one from the stack by means of a separator disc 2 having friction fingers 3 protruding beyond its surface and a cooperating friction shoe 1a, as disclosed in Letters Patent of the United States No. 1,385,468, granted to Charles F. Pfianze on July 26, 1921. This mechanism deposits the blanks singly upon a conveyor belt 4 and beneath rollers 5 and guide bars or frames 6. The conveyor belt 4 travels at such slow speed that the blanks are overlapped or shingled upon it, being arranged in fanned out relation and being carried forward slowly by the conveyor. As seen in Figure 14, provision is made of a roller 7 carried by a lever 8 which is pivoted upon a bracket 9. A spring 10 connected to the tail of the lever 8 and to the bracket pulls upward on the tail of the lever, and hence urges the roller 7 toward the conveyor 4. The bracket 9 is adjustably mounted upon a bar 11, being adapted to be secured in various adjusted positions by means of a set screw 12. By adjusting the bracket 9 along the bar 11 the roller 7 may be located at the proper distance (substantially a blank length) from the line of contact of rollers 2a and 2b which coat with the cylinder 2 in removing the blanks from the stack and feeding them rapidly away. Beyond the rollers 5 the blanks pass beneath a pair of parallel belts 13 which run upon pulleys 14, 15 and 16, and which pass around a drum 17 in position to bear against the conveyor belt 4. From the drum 17 the blanks pass onto a wide belt 18 that runs upon a cylinder 19 and upon pulleys 20, 21 and 22. The blanks are held against the belt 18 by the belt 4 for part of their travel around the cylinder 19, and then by two narrow belts 23 which run upon pulleys 24, 25, 26, 27, 28 and 29. In the course of their travel around the cylinder 19 the blanks come beneath a gummer 30 which applies gum to the exposed trailing margins of the blanks (the top or sealing flaps). The blanks are delivered by the belts 18 and 23 to a drying conveyor 31. This conveyor comprises a pair of narrow chain belts 32, each driven by sprockets 33 and 34. Rails or skids 35 support the upper stretch of the chains 32, and an air chest 36 blows air against the gummed faces of the blanks from below. The belt 32 travels at a slightly higher speed than the belts 18 and 23, and hence serves to fan the blanks out a little more, so as to avoid liability of two or more of the blanks sticking together. A wide belt 37 runs above the belts 32 in position to hold the blanks against shifting while they are carried by the belts 32. The belt 37 runs upon and end roller 38, intermediate rollers 39, a delivery end roller 40, and a large cylinder 41. Near the delivery end of the belts 32 provision is made of a hold-down conveyor consisting of two narrow parallel belts 42 that run upon pulleys 43, 44, 45, 46, 47 and around cylinder 41 in positions to bear against the blanks supported on the belt 37. As the blanks emerge from beneath the belts 42, they continue upon the belt 37 to the roller 40, the stretch of belt 37 between cylinder 41 and roller 40 being supported by a table 48. A bar 49 detachably mounted on a portion of the machine frame 50 by means of screws 49a carries a bracket 51 which is adjustable longitudinally of the bar 49 and which may be secured in adjusted positions there-

on by means of a set screw 51b. The bracket 51 pivotally supports a lever 53 which carries a roller 54 at one end, and which has its opposite end connected to the bracket by means of a spring 55. The spring acts to press the roller down against the blanks supported by belt 37.

At this point the blanks have had their sealing flaps gummed and dried and are in fanned out relation. They are ready for delivery to the mechanism for gumming and folding the side and bottom flaps and for folding the sealing flaps.

At times, however, it is desired to use the machine for making envelopes for carrying second class mail matter, and in such case it is not desired to gum the top flaps. While the mechanism thus far described is adapted to deliver the blanks automatically to the mechanism for performing the subsequent operations referred to, it may also be rendered idle independently of the remainder of the machine, and provision is made for substituting means for supplying fresh blanks in stacked form to such subsequent mechanism.

The means for taking the blanks into the side flap folding and gumming mechanism comprises a disc 50a having friction studs 51a thereon, a wide roller 52a, and narrow rollers 53a which cooperate with the roller 52a. The mechanism is like the similar separator mechanism disclosed in Figure 1. Provision is made of a support 54a above the table 48 on which a shelf or table 55a may be mounted for supplying blanks to the separator mechanism 50a-53a. When fresh blanks are to be fed from a stack to the separator mechanism, the bar 49 is removed from the machine and the table 55a is put in place. Provision is made of means adjustable to bridge the gap between the conveyor 37 and the separator mechanism 50a-53a or to bridge the gap between the table 55a and the separator mechanism. To this end provision is made of brackets 56 having slots 57 therein. The brackets are adapted to be fixed in position by screws 58 that pass through the slots and nuts 59 threaded on the ends of the screws. When the nuts 59 are loosened the brackets may be moved bodily and adjusted angularly to place a shelf 60 carried by them either in position to form a continuation of the belt 37 or in position to form a continuation of the table 55a. A leaf 61 is hingedly connected to the shelf 60 to bridge the space between the shelf 60 and the disc 50a. A screw 62 threaded through a fixed bar 63 bears against the under side of leaf 61 and may be adjusted to locate the forward end of the leaf 61 at just the distance desired from the disc 50a.

The remainder of the mechanism operates the same, regardless of whether the blanks are taken from the conveyor 37 or from table 55a. The ensuing description may, therefore, be considered from either viewpoint.

The roller 52a and the disc 50a are rotated rapidly enough to cause the blanks to be delivered in spaced out, non-overlapping relation. The blanks are delivered onto a conveyor comprising a pair of chains 64 provided with fingers 65. The chains 64 run upon sprockets 66 and 67. The fingers 65 engage the blanks at the junctions of the top and side flaps and serve to align and accurately time the blanks. Hold-down bars 68 are provided in opposition to the chains 64, and any suitable means may be provided for supporting the active lengths of the chains between the ends thereof. From the conveyor chains 64 the blanks pass a scoring mechanism 69 which forms

fold lines between the body portions and the side flaps of the blanks. The blanks then pass through a feeding couple 70 and thence to a side flap gumming and folding mechanism 71 which is desirably identical with that disclosed in Figures 8 and 9 of my pending application Serial No. 554,704, filed August 3, 1931, for Envelope machines.

From the side flap folding mechanism the blanks pass between center seam and side crease pressing rollers 72 and 73, and thence to a blank turning mechanism 74 like that disclosed in my pending application Serial No. 548,791, filed July 6, 1931, for Envelope machines, the mechanism comprising a pair of cones and being preferably as disclosed in Figures 6 and 7 of said application. This mechanism operates to turn the blanks about their forward right hand corners, that is to say, about the intersection of the leading and right hand edges, through a right angle so that the blanks no longer advance bottom edge first, but instead advance side edge first. The turned blanks are delivered onto a conveyor 75 which in turn delivers them to a mechanism 76 which side-aligns the blanks and carries them to a higher level. This mechanism comprises an inclined conveyor consisting of a pair of chains 77 which run upon large sprockets 78 carried by a lower shaft 79 and upon large sprockets 80 carried by an upper shaft 81. Between the sprockets 78 and 80 the shafts 79 and 81 carry, respectively, cylinders 82 and 83. A roller 84 and a guide plate 85 coat with the cylinder 82 to feed and guide the blanks around the cylinder. As soon as the blanks leave the bight formed by the feed roller 84 and the cylinder 82 they stand stationary until overtaken by fingers 86 carried by the chains 77. The fingers act to square the blanks and to advance them. As each blank reaches the top of the cylinder 82, one edge thereof enters a channel-shaped side gauge 87. Between the cylinders provision is made of a belt conveyor for urging the blanks sidewise toward the side gauge 87. This conveyor comprises a belt 88 that runs on pulleys 89 and is supported in its active stretch by a table or bar 90. Balls 91 carried by an overlying bar 92 bear against the blanks in opposition to the active stretch of conveyor belt 88. The belt 88 travels obliquely to the path of the chain 77 and tends to urge the blanks frictionally toward the channelled gauge 87.

The length of travel of the conveyor 88 is so short that there is a danger that the blanks will not be perfectly side-aligned by it. Provision is therefore made of a horizontally disposed mechanism 93 which is a substantial duplicate in structure and an exact duplicate in function and operation of the mechanism 76. The blanks are delivered to this second side-aligning mechanism by the first.

From the second side-aligning mechanism 93 the blanks are passed through a scoring couple 94 which scores lines at the junctions of the top and bottom flaps with the body of the envelope. The blanks pass thence to a mechanism 95 which gums the bottom flap and folds the bottom and top flaps. The mechanism 95 is generally similar to the gumming and folding mechanism disclosed in Figures 4 and 5 of my pending application Serial No. 554,704, hereinbefore referred to. It will be observed, however, that in passing through the side-aligning and elevating mechanism 76 the blanks are inverted so that they enter the mechanism 95 seam side downward. The

mechanism 95 is therefore required to gum the under face of the bottom flap and to fold the top and bottom flaps downward and inward. Provision is accordingly made of a center supporting and feeding conveyor belt 96 which runs through the entire length of the mechanism 95. This belt runs upon pulleys 97, 98, 99, 100 and 101, and has its active stretch supported intermediate the ends thereof by any suitable means (not shown). Provision is also made of side belts 102 which bear against the lower margins of the body portion of the blank and which run upon pulleys 97, 103, 104, 105 and 101. Above the plane of blank feeding provision is made of a pair of side belts 106 which extend throughout substantially the entire length of the mechanism 95. These belts run upon pulleys 107, 108, 109, 110, 111 and 112. They are held down by a series of intermediate rollers 113 and act in direct opposition to the belts 102 and to folding belts 114. A further conveyor belt 115 runs upon pulleys 116 and 117 and acts in opposition to the conveyor belt 96. This belt also has rollers like 113 cooperating with it.

The belts 96, 102 and 106 carry the blanks so that the bottom flaps pass between a gum roller 118 and an opposed channeled presser 119. The blanks then travel past a pair of downwardly and inwardly inclined folding bars 120 which fold the top and bottom flaps through substantially a quadrant. In passing the bars 120 the blanks leave the conveyor belts 102 and pass over bars 121 which carry rollers 122 that bear against the blanks from below in opposition to the belts 106. The bars 121 at the side of the blank adjacent the top flap carries a folding blade 123 about which the top flap is folded, but no such folding bar is provided adjacent the bottom flap for the reason that the wet gum on the bottom flap would be pressed against the bar. The center conveyor 96 is of especial utility in supporting the blanks at this point.

The folding belts 114 run upon pulleys 124 and 125 and upon intermediate rollers 126 which cause their active stretches to be turned from substantially vertical to substantially horizontal positions, so that they are adapted to fold the top and bottom flaps in against the body portion of the blank. They also act to marginally support the blanks and assist in feeding the blanks to a discharge couple 127, and thence to a discharge conveyor 128.

I have described what I believe to be the best embodiments of my invention. I do not wish, however, to be confined to the embodiments shown, but what I desire to cover by Letters Patent is set forth in the appended claims.

I claim:

1. In an envelope machine, in combination, an outgoing stretch of mechanism including successive means for gumming, folding, and adhesively uniting the side flaps, means for transferring the blanks to an upper level, and a return stretch of mechanism at said upper level including successive means for gumming the bottom flap and folding the bottom and top flaps.

2. In an envelope machine, in combination, a linearly disposed, outgoing stretch of mechanism including successive means for gumming, folding, and adhesively uniting the side flaps, means for transferring the blanks to a different level, and a return stretch of linearly disposed mechanism located at said different level and in the same longitudinal, vertical plane as the first including successive means for gumming the bottom flap and folding the bottom and top flaps.

3. In an envelope machine, in combination, mechanism including successive means for gumming and folding the side and bottom flaps of blanks and folding the top flaps, and means selectively usable for supplying blanks to said mechanism, the first including successive means for gumming and drying the top flaps of fresh blanks and delivering them in fanned out relation to said mechanism, and the other comprising means for delivering fresh blanks in stack form to said mechanism.

4. In an envelope machine, in combination, mechanism including successive means for folding the side, bottom and top flaps of blanks, and means selectively usable for supplying blanks to said mechanism, the first including successive means for gumming and drying the top flaps of fresh blanks and delivering them in fanned out relation to said mechanism, and the other comprising means for delivering fresh blanks in stack form to said mechanism, said mechanism including means adapted to individually space the blanks presented either in fanned out form or in stack form.

5. In an envelope machine, in combination, a linearly disposed gummer and drier for the top flaps of blanks adapted to be rendered idle at will, a linearly disposed mechanism including successive means for gumming, folding, and adhesively uniting the side flaps, said mechanism being doubled back over the drier and being adapted to take blanks either from the drier or from a stack, and linearly disposed mechanism including successive means for gumming the bottom flap and folding the bottom and top flaps, said last mentioned mechanism being doubled back over the side flap gumming and folding mechanism.

6. In combination, a linearly disposed mechanism including successive means for gumming and drying the sealing flaps of envelope blanks, a second linearly disposed mechanism including successive means for gumming and folding the side flaps of the blanks, and a third linearly disposed mechanism including successive means for gumming the bottom flaps and folding the top and bottom flaps of the blanks, said mechanisms being located at three separate levels one above the other, and being all disposed substantially in the same vertical, longitudinal plane.

7. In an envelope making machine, in combination, a linearly arranged mechanism including successive means for gumming the side flaps and folding them upward and inward, means for transferring the blanks to a different level and reversing the direction of travel thereof, said means acting to invert the blanks, and mechanism including successive means for folding the top and bottom flaps downward and inward, including folding instrumentalities, and means between said instrumentalities supporting and feeding the blanks continuously through said mechanism.

8. In a machine for making containers of the type having flaps foldable on lines angularly disposed with reference to each other, the combination of a run of mechanism for conveying container blanks and for folding flaps of the blanks on lines of fold parallel to the line of movement of the blanks, upon said run, means for turning said partly folded blanks through an angle corresponding to the angle defined by the lines of fold, and a second run of mechanism for conveying said blanks in the opposite direction and for folding other flaps on lines of fold parallel

to the line of movement of the blanks upon said reverse stretch.

9. In an envelope machine, in combination, an outgoing stretch of mechanism for folding the side flaps of a blank, means for transferring the blank to an upper level, and a return stretch of mechanism at said upper level for folding the bottom and top flaps.

10. In an envelope machine, in combination, an outgoing stretch of mechanism for folding the side flaps of a blank, means for transferring the blank to a different level and a return stretch of mechanism at said different level for folding the bottom and top flaps.

11. In a machine for making containers of the type having flaps foldable on lines angularly disposed with reference to each other, the combination of a run of mechanism for conveying container blanks and for folding flaps of the blanks on lines of fold parallel to the line of movement of the blanks, means for transferring said partly folded blanks to a higher level, means for turning said partly folded blanks through an angle corresponding to the angle defined by the lines of fold, and a second run of mechanism at said higher level for conveying said blanks in the opposite direction and for folding other flaps on lines of fold parallel to the line of movement of the blanks.

12. An envelope machine having the features claimed in claim 3, and in which the mechanism referred to includes a blank separator, in which the first and second blank supplying means comprise, respectively, a conveyor for feeding blanks to the separator, and a table for supplying blanks to the separator, and which further includes a bridge adjustable either to a position for bridging the space between the conveyor and the separator or to a position for bridging the space between the table and the separator.

13. An envelope machine having the features claimed in claim 4, in which the mechanism referred to includes a blank separator, in which the first and second blank supplying means comprise, respectively, a conveyor for feeding blanks to the separator, and a table for supplying blanks to the separator, and which further includes a shelf, means for securing the shelf in adjusted positions to form an extension either of the conveyor or of the table, a leaf hinged to the shelf, and means for adjusting the leaf relatively to the shelf.

14. In an envelope making machine, in combination, mechanism including successive means for folding the side and bottom flaps of envelope blanks, a blank separator for individualizing blanks and delivering them in spaced out relation to said mechanism, and means selectively useable for supplying blanks to said separator, the first including successive means for gumming and drying the closure flaps of fresh blanks and delivering them in fanned out relation to the separator, and the other comprising means for supplying fresh blanks in stack form to the separator.

15. In an envelope machine, in combination, mechanism including successive means for folding the side flaps and the bottom flap of each envelope blank, means for gumming and drying the closure flaps of blanks and delivering the blanks to said mechanism, and means for supplying blanks from a stack directly to said mechanism, independently of the closure flap gumming and drying means, when the production of envelopes having unguammed closure flaps is desired.

16. In an envelope making machine in combi-

nation, a mechanism for converting blanks into envelopes, a blank separator for individualizing blanks and delivering them in spaced out relation to said mechanism and means selectively usable for supplying blanks to said separator, the first including successive means for gumming and

drying the closure flaps of the blanks and delivering them in fanned out relation to the separator and the other comprising means for supplying blanks in stack form to the separator.

5

ABRAHAM NOVICK.
